UNITED STATES PATENT OFFICE.

CHARLES H. CHAPMAN, OF SHIRLEY, ASSIGNOR TO THE STANDARD SPINDLE COMPANY, OF AYER, MASSACHUSETTS.

SPINDLE FOR SPINNING-MACHINES.

SPECIFICATION forming part of Letters Patent No. 249,142, dated November 1, 1881.

Application filed March 11, 1881. (No model.)

To all whom it may concern:

Be it known that I, CHARLES H. CHAPMAN, of Shirley, in the county of Middlesex and State of Massachusetts, have invented certain Improvements in Spindles for Spinning-Machines, of which the following is a specification.

This invention relates to spindles for spinning-machines of the class adapted to be oiled by atmospheric pressure, and it has for its object to provide such a spindle embodying certain improvements over any now in use.

To this end my invention consists, first, in certain improvements whereby the spindle may be steadily run at a high speed with the minimum of power.

The invention consists, secondly, in certain improvements in construction, whereby the lubricating operation is more perfectly performed.

The invention consists, thirdly, in certain improvements in the spindle-whirl, whereby a band can be wound once, or more than once, around the same, and at the same time produce an even and positive rotation of the spindle.

The invention also consists in certain details of construction, all of which I will now proceed to describe, reference being had to the accompanying drawings, forming part of this specification, in which—

Figure 1 represents an elevation of a spindle embodying my invention. Fig. 2 represents a vertical section of said spindle. Fig. 3 represents a similar section with the live-spindle raised upon the standard or dead-spindle. Fig. 4 represents a whirl embodying my invention, having a band wound once and a half around the same. Figs. 5 and 6 represent similar views of whirls as ordinarily constructed.

In all the figures the same letters refer to the same parts.

In the drawings, n represents a spindle standard fitted loosely within a supporting-tube, T , which tube surrounds the standard n and is rigidly secured to the base B . The standard n is secured within the tube T and kept from rotating therein by the pin o , said pin being cut off at such a length as to firmly wedge within the tube T , the principle being

the same as that set forth in my patent of the 50 United States for improvements in spindles, granted July 19, 1881, No. 244,712.

H represents the tip of the spindle, which is held within the shell F by means of the rivet y . The tip H is provided with a step, P , which 55 enters an enlarged cavity in the standard n , said cavity being of such size that the step has no lateral bearing on the sides thereof, but bears only at its lower end, which rests upon a seat, n' , forming the bottom of said cavity. 60 The enlarged cavity prevents any unsteadiness in the motion of the tip in case the step is not exactly concentric with both the tip and shell. It is obvious that if the step were fitted closely in a socket in the standard, so as to have a 65 lateral bearing on the sides of said socket, the slightest eccentricity of the step or of the socket would cause the tip to run unsteadily.

E represents a suction-tube, which is pressed upon the shell F and firmly soldered to said 70 shell through the orificess. The tube E forms an extension extending downwardly from the shell F , and being larger in interior diameter than the diameter of the supporting-tube T , an annular space is left between said tube E and the exterior of the supporting-tube T . The tube E has a shoulder, i , formed on the outer surface of the tube, said shoulder forming a bearing for the whirl D and preventing the 75 whirl from being driven too far down upon the spindle.

K represents a stop, secured to the base B and adapted to limit the upward movement of the whirl when the latter is raised, as shown in Fig. 3. The suction-tube E extends down and 85 around the supporting-tube T , but has no lateral bearing either upon its outer or inner surface after leaving the shell F .

In practice it has been found that when the spindle and its oil-cup are constructed in the 90 ordinary manner, and the spindle is revolving at a high rate of speed, the oil in the cup surrounding the spindle is repelled or thrown away from the spindle, there being also the additional objection that when the shell of the 95 spindle is raised for the purpose of producing a vacuum around the spindle for oiling the same an opening below the shell is formed,

which allows the air to pass down and into the spindle, thereby tending to break the vacuum caused by the vertical movement of the shell upon the standard.

5 To obviate the foregoing objections to the spindle now in common use by my present invention by so constructing the oil-cup that the lower end of the suction-tube E, when in its normal position, will be more closely surrounded 10 by said cup.

The base B is held in position by the screw and nut L in the ordinary way, and is provided with the oil-cup m. The lower part, m', of the oil-cup is contracted in size and formed within 15 the solid portion of the base B. The cup m has a loose-fitting cap, c, which is made in tubular form, and is provided with two outwardly-projecting flanges, f, f', the flange f' resting upon a seat or shoulder formed within the upper end 20 of the oil-cup m. The cup m extends upwardly around the cap c to a height above the flange f' sufficient to prevent the oil from working over the top of the cup. The flange f' is of greater diameter than the cup m, and extends outwardly 25 over the top of said cup, to protect the oil from dust. The cap c surrounds the lower end of the spindle-shell, and is separated therefrom by an annular space. The upper end of the cap c extends upwardly into a recess or cavity formed 30 in the under side of the whirl D.

30 h h represent two orifices, provided for the escape of any oil that may work up over the flange f'.

It will be apparent that by contracting the 35 lower part of the oil cup or reservoir, as described, a narrow annular space is formed within the base B around the spindle, having a limited capacity, and therefore capable of being filled by a small quantity of oil, so that there 40 is less liability of breaking the vacuum when the shell is raised upon the standard than there would be if the reservoir were of the same size at the bottom as elsewhere, the oil having a considerable height in the reservoir, even when 45 a considerable portion of it has been consumed. When the shell F and its inclosing suction-tube E are raised upon the standard until the whirl D strikes the stop K, as shown in Fig. 3, two 50 vacuums will be formed around the spindle, one at Z, between the tip H and the standard n, and one at Q, around the lower portion of the standard n. These two vacuums are of decided 55 advantage in raising oil from the cup m by atmospheric pressure when a small and long standard is employed.

It has also been found in practice that conical shaped whirls as heretofore constructed are impracticable, for the reason that in operation the position assumed by the band upon the 60 whirl affects the speed of the spindle, so as to seriously interfere with the operation of the same. For instance, if the band is tight and the spindle runs hard, the band will assume the position on the whirl shown in Fig. 5, while 65 on the other hand, if the band is loose and the spindle running light, it will take the position

shown in Fig. 6. Besides this, when the band takes either of these positions it overrides and soon chafes or wears off, and becomes a constant source of trouble to the spinner, and 70 greatly lessens the production.

The mode of banding the whirl, it will be seen, is of great importance in practice. When the band is loose and run on a V-shaped whirl it has a constant tendency to jump and slip, 75 and as it is impossible to keep the band from stretching, there must always be in every mill a large number of bands running in such a manner that slack-twisted spots are left in the yarn which will be the cause of bad work whenever the yarn is used. 80

In my invention I make the whirl D of an irregular conical form—that is to say, I cut the upper portion of the cone of said whirl from the point E' midway between the upper and 85 lower flanges of the whirl, or nearly so, to the under side of the upper flange, t, with a less taper than the corresponding lower portion of the whirl, or from the point E' to the flange t', leaving a slight re-entrant angle at the point 90 E'. By forming the whirl in the manner described I overcome the difficulties in banding before alluded to.

The suction-tube E has a flange or projection, 95 p, formed upon its outer surface, the object of said flange being to prevent the oil from rising upon the surface of the tube when the spindle is revolving, as all oil rising in this manner will be thrown at the flange p by centrifugal force. The flange p is located at a point immediately below the cover c.

In the operation of my spindle the supporting-tube T enables the spindle to be run on a very small bearing with great steadiness and with a comparatively small expenditure of power. The construction of the oil-cup and the inclosing of the shell of the spindle within a suction-tube, whereby two vacuum-chambers are adapted to be formed around the standard and over the same when the shell is raised, greatly 105 facilitates the lubrication of the bearing-surfaces, while the described form of whirl overcomes the chafing of the bands and the differences of speed encountered in the use of spindles of the ordinary form. 110

I do not in this case claim the combination of a dead-spindle having an enlarged cavity in its head, and a live shell-spindle having a bearing in the enlarged cavity in the dead-spindle, but reserve the right to make this claim 120 in a future application. 115

Having thus described my invention, what I claim is—

1. The combination, with a standard, n, of the longitudinally-movable shell adapted to be 125 raised to form a vacuum-chamber, Z, at the upper end of the standard, and provided with a suction-tube, E, forming an internal enlargement at the lower end of the shell, whereby, when the spindle is raised a vacuum-chamber, 130 Q, will be formed at the lower portion of the shell, as set forth.

2. The combination of the supporting-tube *T*, rigidly attached to a base, *B*, the standard *n*, fitted loosely in said tube and secured therein by a pin, *o*, and the shelf *F*, supported by 5 the standard, and provided with the tip *H*, as set forth.

3. The combination, with the standard *n*, and the oil reservoir or cup at the base thereof, of the shell *F*, having the suction-tube *E* 10 projecting into the oil-reservoir, and having the flange *p*, to prevent the oil from working up the outer surface of said tube, as set forth.

4. The combination, with the standard *n* and the vertically-movable shell *F*, supported 15 by the standard, and provided with the downwardly-projecting suction-tube *E*, of the oil-reservoir *m*, contracted at its bottom into a narrow annular space, *m'*, adapted to contain 20 the lower end of the suction-tube, and of sufficient depth to prevent said tube from being withdrawn from said space by the upward movement of the shell and spindle caused by the act of dropping the bobbin, substantially as described.

25 5. The shell *F*, having the suction-tube *E*,

provided with a shoulder, *i*, combined with the whirl *D*, as set forth.

6. The combination of the standard *n*, the shell *F*, having the whirl *D*, which is provided with an annular space in its lower side, the oil-reservoir *m*, formed with an interior shoulder 30 near its upper end, and a cap composed of a tube surrounding the lower end of the spindle-shell, and provided with flanges *f f'*, the latter resting on the shoulder of the reservoir and 35 the former projecting over the upper edge of said reservoir, as set forth.

7. The flanged whirl having its periphery between its flanges composed of two cone frustums of different inclinations, having a re-entrant angle at their meeting-point, substantially as and for the purpose specified. 40

In testimony whereof I have signed my name to this specification, in the presence of two subscribing witnesses, this 5th day of March, 45 A. D. 1881.

CHARLES H. CHAPMAN.
